UNITED STATES PATENT OFFICE.

FREDERICK L. FAY, OF MARSHALLTON, DELAWARE, ASSIGNOR TO STANDARD-TRUMP BROTHERS MACHINE COMPANY, OF WILMINGTON, DELAWARE, A CORPORATION OF DELAWARE.

CIRCULAR-KNITTING MACHINE.

Application filed December 3, 1924. Serial No. 753,572.

The object of my invention is to provide a machine for knitting circular fashioned fabric, such as the leg of a stocking, and to effect the fashioning by the successive introduction (or successive removal) of needles.

The fabric is knit, in the preferred embodiment of my invention herein shown, by providing two stationary banks of needles—
10 a front bank and a rear bank, or an outer bank and an inner bank—arranged arcuately and concentrically; and two cam cylinders similarly arranged, rotating in opposite directions, one—an inner cylinder—
15 carrying cams for actuating the inner bank of needles, and the other—an outer cylinder—carrying cams for actuating the outer bank of needles. The cams are positioned so that only one bank of needles is being operated at a time, and so that, when one bank of needles has knit a course of stitches, the
20 yarn is transferred from the last needle of such bank to one of the approximately opposite needles of the other bank, on which another course of stitches is knit in the reverse direction. These two courses of
25 stitches, taken together, comprise one complete circumferential course of knitting. The yarn is then transferred to the first
30 needle of the first bank, on which another course of stitches is knit, which course is, in effect, a continuation of the preceding course. Thereby there is formed a succession of circumferential courses of knitting; or, more
35 accurately expressed, one long spiral course, as in any ordinary circular knitting machine.

To effect the fashioning of the fabric, needles at or near opposite ends of the two banks are moved into action and the thread is transferred from the last active needle of one bank to an approximately opposite theretofore inactive needle of the other bank, whereby the diameter of the circular fabric
40 is increased a length equal to that of a stitch. By successively moving into action approximately opposite needles of the two banks, the diameter of the circular fabric is gradually increased—that is, the circular fabric is
45 fashioned—until any desired maximum diameter is being knitted.

It will be understood that, in the art of flat knitting machines, as well as in the art

of rotary-reciprocatory circular knitting machines, there are various specific modes of adding needles, one at a time, in order to gradually widen the fabric. Any of the known methods of adding needles may be utilized in carrying out my invention.

It is preferred to arrange a number of double banks of needles around a circumference and to provide as many knitting cams on each cam cylinder as there are double banks of needles; each knitting cam of the inner cam cylinder engaging and actuating, in its rotation, successively all the inner banks of needles, and each knitting cam of the outer cam cylinder engaging and actuating, in its rotation in the opposite direction, successively all the outer banks of needles.

The double banks of needles should be spaced apart a distance at least equal to the length of a complete bank of needles, so that it will be possible to complete a course of stitches on one bank of needles simultaneously with, or before, the beginning of a course of stitches on the other bank.

The advantages of producing a circular fashioned fabric on a circular machine are, of course, obvious; especially where the fashioning is accomplished without any interruption of the continuous rotary movement of the rotatable elements.

It is also obviously advantageous to be able to simultaneously knit a plurality of webs. If eight double banks of needles are operated by cams having one-eighth of the angular speed of rotation common to that in an ordinary circular machine, and a circumferential speed equal to that on an ordinary circular machine, the production will be eight times that of an ordinary circular machine; or the circumferential speed of the cams may be advantageously reduced and the machine will still have multiple times the production of an ordinary circular machine.

In the drawings:

Fig. 1 is an elevation of the machine partly in section.

Fig. 2 is an enlarged plan view, with the 100 yarn spools and yarn tension devices removed.

Fig. 3 is a still further enlarged radial section through the circumferential part of the machine.

Fig. 4 is a detail view of the mechanism.

for moving the needles successively into action to effect a gradual increase in diameter of the fabric.

Fig. 5 is an end view of the same mechanism together with a radial section, similar to Fig. 3, through the knitting cylinders and cam cylinders.

Fig. 6 is a detail plan view of the cam ring for actuating the needle levers for moving the needles into and out of action.

Referring first to Fig. 3: 6 is the outer stationary needle cylinder; 7 the inner stationary needle cylinder; 8 the outer rotating cam cylinder; 9 the inner rotating cam cylinder.

The outer stationary needle cylinder 6 is provided with radial grooves in which needles 60 are adapted to reciprocate longitudinally to effect ordinary knitting. The longitudinal reciprocating knitting movement is effected by knitting cams 80 on the outer rotating cam cylinder 8. Sinkers 61 are provided, one for each needle. These sinkers are pivoted on the knitting cylinder and are provided with projections engaging a cam groove formed between the upper end of the cam cylinder 8 and flanged plates 81 secured to the cam cylinder.

The inner stationary needle cylinder 7 carries in the same way needles 70 operable by knitting cams 90 on the inner rotating cam cylinder, and sinkers 71 operable by a cam groove formed between the upper end of the cam cylinder 9 and flanged plates 91 secured thereto.

There are any desired number (eight are shown) of double banks of needles 60 and 70. On Fig. 2, these double banks of needles are lettered *a*, *b*, *c*, *d*, *e*, *f*, *g* and *h*. The two cam cylinders 8 and 9 are continuously rotated in opposite directions by the following mechanism, shown in Figs. 1 and 2:

On a driving shaft 11 is secured the usual fixed pulley 12 and loose pulley 13 and a bevel pinion 14 which engages a bevel pinion 15, whose shaft turns on a bracket 63 secured to the frame of the machine. The shaft of pinion 15 carries a spur pinion 16, which engages a gear or rack 82 carried by the rotatable cam cylinder 8, whereby the latter is continuously rotated.

On the driving shaft 11 is secured a bevel pinion 17, engaging a bevel pinion 18, whose shaft turns in a bracket 73 secured to the frame of the machine. The shaft of pinion 18 carries a spur pinion 19, which engages a gear or rack 92 carried by the rotatable cam cylinder 9, whereby the latter is continuously rotated.

Certain of the needles 60 are movable into and out of action by means of needle levers 64 (see Fig. 3), which are operated by cam rings 65 (see Figs. 3 and 6) circumferentially shiftable on the machine frame.

The purpose of so moving the needles into and out of action and the mechanism for so doing is hereinafter described. Similarly, certain of the needles 70 are movable into and out of action by means of needle levers 74 operable by cam rings 75 on the machine frame.

The needle cylinders 6 and 7 are mounted on the main frame 20 of the machine (see Fig. 1), on which is also mounted centrally, a post 21 carrying the yarn spools 22 and a frame 23 comprising a number of radial arms (see also Figs. 2 and 3), each carrying a yarn feed 24 adjacent the needle hooks and a yarn tension device 25. The frame 23 is oscillatable back and forth, for a distance about equal to the length of one of the double needle banks *a*, *b*, etc., by the following mechanism.

A drum 27 (see Fig. 2) turning in bearings on the frame 20, is operable from the driving shaft 11 by means of a train of gears 26. A bar 28 connecting two adjacent arms of the frame 23 has a pin engaging a spiral groove 29 on the drum 27. The groove 29 is so shaped that, in the rotation of the drum, it imparts the described oscillatory movement to the frame 23.

In knitting circular webs of uniform diameter, the operation of the machine is as follows:

Yarn is simultaneously feeding to the needles of all the eight banks of needles, *a*, *b*, *c*, *d*, *e*, *f*, *g*, etc. Assume that yarn is being fed to the first needle of each of the outer banks of needles 60. As the outer cam cylinder 8 rotates, the knitting cams 80 carried thereby successively move the needles 60 into and out of action until all the needles 60 have so operated, whereby there is formed, by each outer bank of needles 60, a course of stitches of a length equal to one-half the circumference of the circular web to be knitted. At the same time the yarn-feed frame 23 has moved along with the cam cylinder 80 in the same direction and at the same rate of speed. The knitting cams 80, in their continued rotation, now travel beyond the respective banks of needles 60 which they have been actuating into the open space between adjacent banks of needles, and while traveling over this open space are ineffective to actuate any needles.

During the described rotation in one direction of the cam cylinder 8, the cam cylinder 9 is rotating in the opposite direction; and when the last needle 60 of each bank has been actuated, the cams 90 begin to actuate the needles 70 of the inner banks of needles; the yarn passing from the last needle of each outer bank of needles 60 to the first needle of each inner bank of needles 70; it being understood that the "first" needle of each outer bank is approximately op-

posite the "last" needle of each inner bank. The cams 90 successively move the needles 70 into and out of action until all the needles 70 have been so operated, whereby there 5 is formed, by each inner bank of needles, a course of stitches of a length equal to one-half the circumference of the circular web to be knitted. Together with the half course previously formed on needles 60, the 10 half course formed on the needles 70 of the same double bank completes one complete circumferential course of stitches. During the operation of needles 70, the yarn feed frame 23 has moved in the reverse direction 15 to that previously described; that is, it has moved along with the cam cylinder 90 in the same direction and at the same rate of speed.

The spaces between double banks of needles are, preferably, equal to the lengths of the banks. It will, therefore, be understood that while the outer needles 60 of the double banks are being actuated by the knitting cams 80, the knitting cams 90 are traveling 20 across the spaces between double needle banks; that when the inner needles 70 of the double banks are being operated by the knitting cams 90, the knitting cams 80 are traveling across the spaces between double 25 needle banks; and that, therefore, as soon as a half course of knitting has been completed by the needles of one bank, the knitting of the other half of a course begins on the needles of the other bank. Therefore, 30 in one complete rotation in opposite directions of the cam cylinders, there are knit eight complete circumferential courses of as many different webs.

The mode of operation of the mechanism 40 for producing a circular knitted web having been described, I will now proceed to describe the mechanism for widening the fabric so as to produce a circular web of gradually increasing diameter; in other 45 words, the fashioning mechanism.

I have hereinbefore referred to the needle levers 64 and 74, which (see Fig. 3) are operable by cam rings 65 and 75 respectively to move their corresponding needles 60 and 50 70 respectively into action. In order to fashion the web, it is necessary to move into action one or more needles at or close to the end of one bank and one or more approximating needles at or close to the end of the other bank; to then, in the next course, or 55 in one of the succeeding courses (dependent on whether the increase in diameter is to be abrupt or gradual) again move into action a needle or needles of each bank, and to 60 continue this operation of successively moving into action approximately opposite needles of the two banks until the fabric has been increased in diameter to the extent desired. In Fig. 3, I have shown a needle 65 60 of the outer bank out of operative posi-

tion (that is, out of operative relation with one of the knitting cam 80), while a needle 70 of the inner bank is shown in operative position in engagement with one of the knitting cams 90. The mechanism for thus 70 successively moving into action the needles of one bank (say the inner bank) is shown in detail in Figs. 4, 5, and 6.

On a pattern shaft 30 are two sprockets 31 and 32 carrying respectively pattern 75 chains 33 and 34. Pivoted on the pattern shaft 30 is a lever 37 carrying a pawl 36 engaging a ratchet wheel 35 secured to the shaft 30. The lever 37 has on its end a roller 38 engageable by a cam 39 on the cam 80 cylinder 8. There may be one or two or four or eight cams 39; but assuming that there is one, then, once during each rotation of the cam cylinder, the lever 37 is swung on its pivot to cause the pawl 36 to 85 engage the ratchet 35 and turn the shaft 30 and the sprockets 31 and 32 thereon to advance each of the pattern chains 33 and 34 a distance of (say) one link.

Secured to the machine frame is a bracket 90 66 carrying a vertical shaft to which is fixedly secured a lever 40. A holding pawl 42 is pivoted on this shaft. A shifting pawl 41 is pivoted on the lever 40 between the latter's pivot and its free end. Each of 95 these pawls engages a ratchet 43 on the needle-actuating cam ring 65 and is adapted to be swung out of engagement with the ratchet by the lugs on one or the other of the pattern chains.

The free end of a lever 45, also secured to the vertical shaft, has a cam face which is in line of movement of a cam 44, on the cam cylinder 8, having a similarly inclined face.

When the parts are in the position shown in Fig. 4, at each rotation of the cam cylinder 8, the cam 44 strikes the lever 45, swings it on its pivot and advances the pawl 41 the distance required to push the ratchet 43 forward and turn the cam ring 65 the 110 distance required to move into action one of the needles 60. During the knitting of that part of the fabric which is of minimum diameter, a series of lugs on the pattern chain 33 travels under the tail of pawl 41 115 and retains the pawl out of engagement with the rack 43; the cam ring 65 being then in position to hold all the needle levers 65 in position to hold the corresponding needles 60 out of position to be engaged by the knitting cams 80. Therefore, while, at each rotation of the cam cylinder 8, the cam 44 hits and swings the lever 45 and the pawl 41, the cam ring 65 is not thereby further advanced. When, however, the pattern 120 chain 31 so far advances that the last lug of the series rides from under the tail of pawl 41, its spring presses this pawl into the position shown in Fig. 4, or into engagement with the ratchet 43, so that, at the next 130

engagement of cam 44 with the lever 45, the pawl 41, in advancing a distance of one tooth, advances the cam ring 65; the holding pawl 42 clicking over one of the teeth of the ratchet 43 and engaging the rear of such tooth and holding the cam ring from slipping back. This advance of the cam ring causes it to swing the needle levers 64 controlling the end needles 60 of the several outer banks of needles into such position that these needles are moved into operative relation with the knitting cams 80.

The operation is repeated at each rotation of the cam cylinder 8 until all of the needles 60 that are provided with needle levers are successively moved into position to be operated by the knitting cams 80. During the repetition of this operation, the cylindrical fabric is being gradually widened until, 20 when the last lever-controlled needle 60 is moved into knitting position, a cylindrical fabric is being knit of maximum diameter.

The inner cam ring 75 is directly connected with cam ring 65 by one or more crossbars 50, whereby the inner ring and the needle levers 74 controlled thereby operate needles 70 of the inner bank in harmony with those of the outer bank. By this means corresponding needles of the two banks are moved into operative position successively. In Fig. 3, one of the needles 70 is shown in operative relation with the knitting cam 90.

It will be understood that, if desired, two or more needles at a time may be moved into operative position; or any other desired progressive actuation of the needles may be effected.

After the conclusion of that part of the knitting which produces a cylindrical web of wide diameter is completed, it is necessary to shift the cam ring 75 back to its original position. This is effected in the following way:

A lug on the pattern chain 34 swings the holding pawl 42 out of engagement with the ratchet 43. At the same time a lug on the pattern chain 33 swings the actuating pawl 41 out of operative position. Thereupon a spring 45, secured at one end to an axial pin 46 on the end of shaft on which the pawl 42 is pivoted, and secured at the other end to cam ring 65, immediately returns the latter to its original position, a stop 47 on the cam ring engaging the pawl 42 and preventing movement of the cam ring beyond its original position. On the next turn of the pattern wheel shaft, the lugs on the pattern chains 34 and 33 ride from under the pawls 42 and 41, which then again move into the position shown in Fig. 4.

While I have described the machine as one in which the fashioning is effected by a successively moving into action needles, to produce a gradual widening, as distinguished 65 from commencing with the knitting of a web

of large diameter and the successive movement of the needles out of action, both of which methods of knitting or modes of operation are known in the art, it should be understood that it is not intended in the 50 claims to limit them to the specific mode of operation described or to exclude equivalent modes of operation.

Having now fully described my invention, what I claim and desire to protect by Letters Patent is:

1. In a knitting machine, the combination with a stationary outer bank of needles and a stationary inner bank of needles, both arranged arcuately with respect to a center, so of two needle actuating knitting rings rotatable about said center in opposite directions and cams carried thereby adapted to respectively actuate the needles of the two banks, said cams being so positioned that the 85 needles of the two banks are actuated thereby successively, pattern mechanism, and means operable by the cam ring and controlled by the pattern mechanism to successively move into action adjacent needles of 90 one of the banks of needles.

2. In a knitting machine, the combination with a stationary outer bank of needles and a stationary inner bank of needles, the two banks of needles extending in planes angular to the horizontal and to the vertical and converging toward a common circumference, one of said banks of needles lying inside, and the other of said banks of needles lying outside, said common circumference of two 95 100 needle actuating knitting cams rotatable in opposite directions respectively within and without said circumference and adapted to actuate the needles of the respective banks.

3. In a circular knitting machine, the combination with a series of double banks of needles arranged circumferentially and spaced apart, each double bank comprising a series of outer needles and a series of inner needles, of two cam cylinders rotatable in 110 opposite directions concentrically with the needles, and a series of needle actuating knitting cams carried by each cam cylinder, the series of needle actuating cams corresponding in number to the series of double 115 banks of needles, each cam of one cylinder being adapted, in the rotation of its cylinder, to successively actuate the several outer banks of needles and each cam of the other cylinder being adapted, in the rotation of 120 its cylinder, to successively actuate the several inner banks of needles.

4. In a circular knitting machine, the combination with a series of double banks of needles arranged circumferentially and spaced apart, each double bank comprising a series of outer needles and a series of inner needles, of two cam cylinders rotatable in opposite directions concentrically 125 with the needles, and a series of needle actu- 130

ating knitting cams carried by each cam cylinder, each cam of one cylinder being adapted, in the rotation of its cylinder, to successively actuate the several outer banks of needles and each cam of the other cylinder being adapted, in the rotation of its cylinder, to successively actuate the several inner banks of needles, said cams being so positioned that the two banks of needles of

10 each double bank are actuated successively.

5. In a circular knitting machine, the combination with a series of double banks of needles arranged circumferentially and spaced apart, each double bank comprising 15 a series of outer needles, and a series of inner needles, of two cam cylinders rotatable in opposite directions concentrically with the needles, and a series of needle actuating knitting cams carried by each cam 20 cylinder, each cam of one cylinder being

adapted, in the rotation of its cylinder, to successively actuate the several outer banks of needles and each cam of the other cylinder being adapted, in the rotation of its cylinder, to successively actuate the several 25 inner banks of needles, said cams being so positioned that the two banks of needles of each double bank are actuated successively, and means to simultaneously move into operative relation with its knitting cams 30 a needle of each bank of needles operable by the same set of knitting cams and to successively move into operative relation with its knitting cams a number of needles 35 of each of said banks.

In testimony of which invention, I have hereunto set my hand, at Wilmington, Del., on this 21st day of Nov., 1924.

FREDERICK L. FAY.
